UNITED STATES PATENT OFFICE.

WILLIAM E. O'BRIEN, OF SWANTON, VERMONT.

WATER HEATER.

Application filed February 24, 1923. Serial No. 620,930.

This invention is a heater for maintaining water at the desired temperature for house heating purposes.

One of the objects of the invention is to provide a device of simple construction, which may be connected with a radiator or the like, and having means whereby water to be supplied to said radiator may be heated by extraneous means, such as an oil lamp, electric light, gas flame, or coal stove. A further object is to provide a heater having flues which are flat and deep, and proportioned to provide maximum heating surfaces for any given volume of water to be heated. A further object is to provide means for insuring a substantially perfect water circulation.

The invention will be hereinafter fully set forth and particularly pointed out in the 20 claim.

In the accompanying drawing:—

Figure 1 is a side view illustrating a heater constructed in accordance with the invention. Figure 2 is a top plan view thereof. 25 Figures 3 and 4 are vertical sectional views taken at right angles to each other.

Referring to the drawing, the heater is illustrated in the form of a casing, circular in cross section, provided with annularly spaced inner and outer walls 10 and 11, joined together at their tops 12, and bottoms 13. The top 12 and bottom 13 are each constructed of an annular member of U-shape in cross section as shown, so as to 30 provide flanges extending vertically in a manner to engage the inner surface of the wall 11 and the outer surface of the wall 10. By this means a proper spacing between the walls 10 and 11 is maintained to provide an 35 annular water chamber. A cold water inlet pipe 15, connected with any suitable source of supply, communicates with the lower portion of said annular chamber 14, and an outlet pipe 16 leads from the top thereof. The 40 pipe 16 may lead to any suitable point where the hot water may be utilized, or the pipes 15 and 16 may be connected with the return and supply pipes, respectively, of a hot water radiator.

Extending transversely across the circular space surrounded by the chamber 14, are a plurality of straight parallel water chambers 18, being connected to and communicating with the chamber 14 at opposite positions, the spaces between said water cham-

bers allowing for the passage of hot air and heated gases emanating from a source of heat, such as a lamp or stove (not shown), placed directly beneath the device. It will be noted that the straight water chambers 45 18 are somewhat shorter in length than the length of the casing 14, so as to allow of circulation of heat and air under and over said water chambers, the ends of said chamber being approximately equidistant from 50 the planes of the top and bottom of the chamber 14.

In operation, a suitable heating device is placed beneath the casing in such position that the heat will circulate around and 55 between the water chambers 18, and also impinge against the inner wall 11 of the chamber 14. In this manner a very large area is presented to the action of the heat, and the temperature of the water is quickly 60 raised to a degree sufficient to insure circulation. With the pipes 15 and 16 connected with a radiator, the circulation set up by the heated water is sufficient to maintain 65 the necessary circulation through the radiator.

The advantages of the invention will be readily apparent to those skilled in the art to which it belongs. It will be particularly observed that a very simple and highly 70 efficient heater is provided, by which a high temperature is maintained with a minimum expenditure of initial heat.

Having thus explained the nature of the invention, and described an operative manner of constructing and using the same, although without attempting to set forth all of the forms in which it may be made, or all of the forms of its use, what is claimed 75 is:—

A heater of the character described comprising a casing provided with annularly spaced inner and outer walls, annular top and bottom members of U-shape in cross section so as to provide flanges engaging the inner surface of the inner wall and the outer surface of the outer wall, respectively, to hold said walls in spaced relation to provide a circular water chamber, a series of narrow, straight-walled parallel water chambers extending diametrically across the space surrounded by said inner wall and attached thereto, said straight chambers opening at their ends into said circular chamber and having their top and bottom edges 105 110

equally spaced inwardly from the top and bottom members respectively, a water inlet pipe extending through the top member and having its discharge end contiguous to the bottom member, and an outlet leading from the upper end of said circular chamber through said top member, said inlet and

outlet being located diametrically opposite to each other and in line with the planes of the respective open ends of said straight ¹⁰ chambers.

In testimony whereof I have hereunto set my hand.

WILLIAM E. O'BRIEN.
